Application December 29, 1949, Serial No. 135,639

19 Claims. (Cl. 177—367)

1 The present application is directed to supervisory and control circuits for coded fire alarm systems, and is a continuation-in-part of my co-pending application, Serial No. 37,910, filed July 9, 1948, now abandoned.

The present invention has particular relation to fault detecting means for closed circuit master code type fire alarm systems, i.e. to improved fault detecting means for detecting and indicating an open, de-energized or grounded circuit condition in the system.

It is common practice to operate systems of this type from a conventional alternating current power or light circuit as a power source. For example, it is customary to use a sixty cycle 110 volt source for this purpose. Usually, such alternating current circuits have one side or the neutral grounded. Thus, there is always the possibility, in a fire alarm system of the type here under consideration, of having a grounded condition occur in the system circuit wiring which could cause a short circuit, damaging the equipment, or initiating a false start of the coding mechanism and thereby causing a false alarm to be sounded, or making the system inoperative without giving a trouble indication until an alarm is initiated. False operation of the system may also result from an accidental opening of the fire station circuit.

Accordingly, among the objects of this invention are: to provide simple, reliable and economical means for detecting and signalling the presence of a fault in a closed circuit master code type fire alarm system; to employ only one-half of the alternating current wave, obtained by the use of half wave rectifiers, for the purpose of electrically supervising all of the circuits, the supervising relays and the windings of the motor on the control panel; to provide means for applying the other half wave of the alternating current as a means for initiating the alarm; to indicate, as soon as it occurs, an open circuit or ground in the system, or the failure of the power supply; to maintain de-energized a control relay which, when energized, prevents operation of the fire bell of the fire alarm system beyond a pre-determined cycle of their operation; to control the energization of the control relay by the application of full wave alternating current and to control the de-energization of the control relay by either shunting down the winding of said control relay by a half wave rectifier connected across the winding of said control relay, wherein both said control relay and rectifier are connected in series with another half wave rectifier,

2 and said rectifiers are connected to conduct the same half wave of alternating current; or by blocking the passage of current through the control relay by a rectifier connected in series with the winding of said control relay, but with the latter rectifier connected in opposition to another half wave rectifier so that when only half wave alternating current is applied, current is blocked from passing through said control relay; to so place the said control relay in the circuit that should it fail to operate only the limiting cycle of operation is lost; to connect the windings of alarm relays and windings of the operating electric motor in series circuit relay with various sections of the fire alarm system so that, as long as the circuit continuity is maintained and circuits remain ungrounded, the trouble alarm contacts are held open; and to provide an independently energized trouble alarm circuit in which the normally open alarm relay contacts are connected.

Other objects of this invention will, in part, be obvious and in part appear hereinafter.

For a more complete understanding of the nature and scope of this invention, reference can be had to the following detail description, taken together with the accompanying drawings in which:

Figure 1 is a circuit diagram of one embodiment of the invention;

Figure 2 is a circuit diagram of a modified embodiment of the invention; and

Figure 3 is a fragmentary circuit diagram illustrating the milliammeter in a different location in the circuit.

Referring now to the circuit diagram of Figure 1, it will be observed that the reference characters 10 and 11 designate line conductors or terminals of an alternating current source 12 which may be a 60 cycle 110 volt source. The conductor or terminal 11 may be grounded as indicated at 13. It is conventional to refer to the grounded conductor or terminal 11 as a neutral conductor where it constitutes the grounded conductor of a polyphase alternating current system. The alternating source 12 is arranged to energize a closed circuit master code fire alarm system, the details of which will be described now.

It will be observed that the system includes fire stations which are indicated at FS1 through FS4. It will be understood that a larger or smaller number of fire stations FS1 through FS4 may be employed as desired and that additional circuits including such fire stations may be employed

within the scope of this invention. However, for purposes of simplicity only four fire stations are shown in the drawing and a single circuit containing them is shown. It will be noted that each of the fire stations includes normally open contacts 14 which are arranged to be closed to complete a circuit between conductors 15 and 16 which interconnect them in the event that an alarm is to be sounded and the conventional glass in a fire station box is broken in order to sound the alarm. The conductor 15 which is looped through the various fire stations to one side of each of the sets of contacts 14 therein terminates at T1 and T4. In like manner the conductor 16 which is looped through the other contacts of the fire boxes terminates at T2 and T3. The terminal T1 is connected through a current limiting resistor R1 to the line conductor or terminal 10. The purpose of the resistor R1 is to limit the current flow from the line conductor or terminal 10 in the event that the conductors 15 or 16, for example, should become grounded. The resistance of the current limiting resistor R1 is such that, even if the terminal T1 were grounded or connected directly to the other line conductor or terminal 11, the current flow therethrough would be of the order of one ampere.

With a view to indicating the condition of the conductor 15, its terminal T4 is connected to one terminal of a winding 19 which has a high impedance and which forms a part of an alarm relay A. The relay A has contacts A1 which are normally open as long as the winding 19 is energized. As indicated, the contacts A1 are connected to an alarm circuit which is energized independently. That is, the contacts A1 are connected to energize a lamp or ring a bell or provide a like signal and the source of current therefor is independent of the source 12 of alternating current. For example, a battery may be employed as the source of independent energization for the alarm circuit to which the contacts A1 are connected.

As illustrated in the drawing, the winding 19 of the alarm relay A is connected through a half wave rectifier HWR1 to a current limiting resistor R2 which is connected in series circuit relation with the windings 20 of fire alarm bells, four of which are illustrated, generally, at FB1 through FB4. The resistor R2 is provided to limit the current which can flow through the windings 20 of the fire bells FB1, etc., so as to provide the proper ringing current. It will be observed that the resistor R2 is connected to a terminal T5 and that the windings 20 are connected in series circuit relation by conductors 21, 22 and 23. The remaining terminal of the winding 20 of the fire bell FB4 is connected to a terminal T6 which may be connected by a conductor 24 to an armature 25 of a series motor, which has a series winding 26. The series motor forms a part of a code mechanism which is indicated, generally, at CM. A winding 27 having a low impedance is connected in series with the series winding 26 of the series motor and constitutes a part of an alarm relay B. The alarm relay B has contacts B1 that normally are held open as shown and, as illustrated, are connected to an alarm circuit which is energized independently and functions in the manner set forth above for alarm relay A. The winding 27 is connected by a conductor 28 to a milliammeter 29 which, in turn, is connected to the neutral or grounded line conductor or terminal 11.

The conductor 24 also is connected through

normally closed main contacts D1 of a control relay, that is indicated generally at D, to the terminal T3 to which the conductor 16 is connected. The control relay D includes a winding 32 which normally is de-energized in a manner to be described presently. The circuit from conductor 16 and terminal T2 extends through a winding 33 of an alarm relay which is indicated, generally, at C. The alarm relay C has normally open contacts C1 which, as shown, are connected to an alarm circuit that is independently energized and functions in the manner described above for the alarm relay A. A conductor 34 interconnects the winding 33 and one side of a half wave rectifier HWR2, this conductor 34 also being connected to one end of winding 32 of the control relay D. The other side of rectifier HWR2 is connected by a conductor 35 to the milliammeter 29 which, in turn, is connected to the neutral or grounded line conductor or terminal 11. The other end of winding 32 of control relay D is connected through conductor 30 with a pair of sealing or holding contacts D2 of relay D, and also with reset contacts 50 which are responsive to the code wheel.

It will be observed that the half wave rectifiers HWR1 and HWR2 are connected between the line conductors or terminals 10 and 11 so that they are arranged to conduct the same half cycle of alternating current. Thus the circuit through these rectifiers may be traced from the line conductor or terminal 10, resistor R1, conductor 15, winding 19, half wave rectifier HWR1, resistor R2, windings 20 of fire bells FB1 through FB4, conductor 24, normally closed contacts D1, conductor 16, winding 33, conductor 34, half wave rectifier HWR2, conductor 35 and milliammeter 29 to the grounded or neutral line conductor or terminal 11. Since the half waves of the same polarity are conducted by the rectifiers HWR1 and HWR2, and since the winding 32 is not in circuit, inasmuch as holding contacts D2 and reset contacts 50 are open, no current flows through the winding 32 under normal supervising conditions and the control relay D remains de-energized and in the position shown in the drawing. In order to energize the winding 32 of control relay D, half waves of opposite polarity of the alternating current are applied to it upon the closing of reset contacts 50, in a manner which will be described presently.

The code mechanism CM now will be described further. It will be observed that the armature 25 of the series wound motor is arranged to drive a reduction gear train that is indicated, generally, at 36, the motor preferably being provided with an adjustable governor. The windings of such series motor can be electrically supervised without the motor creeping, and such motor can have an easily adjusted speed control for obtaining a different speed or tempo of the coded alarm to meet the requirements of different customers. A synchronous or shaded pole motor may be used instead of a series type motor if adjustable speed control is not required, as I shall later describe in connection with Figure 2. For illustrative purposes, the reduction gear train 36 is shown as comprising a pinion 37 and a gear wheel 38. However, it will be understood that these are shown and described solely for illustrative purposes and that the gear reduction actually may be obtained by using a number of pinions and a number of gear wheels as will be understood readily. The gear wheel 38 is arranged to drive a code wheel 39 which has teeth 40 on its periphery

that are arranged to effect the closing of normally open code contacts 41 which, as shown, are connected in a conductor 42 that extends from the function between the half wave rectifier HWR1 and current limiting resistor R2 and the neutral or grounded line conductor or terminal 11. It will be understood that the contacts 41 are controlled by the code wheel 39 in such manner as to operate the fire bells FB1 through FB4 and to provide the fire alarm signal determined by the code number cut in the periphery of code wheel 39. This is usually 4-4-4-4. In order to insure that the code wheel 39 revolves the required number of revolutions to effect the proper functioning of the code mechanism CM and to give the required signal, full cycle contacts 44 and 46 are provided. The contacts 44 are operated by a pin 43 carried by the code wheel 39 and they control the stopping position thereof. The contacts 44, as shown, are connected by conductor 45 to the energized conductor 10. Full cycle contacts 46, as shown, are operated by a cam on the hub of the pinion 37 and they are effective to cause the code wheel 39 to revolve four times for each cycle of operations, i. e. four revolutions of the code wheel 39 for each revolution of the pinion 37. The contacts 46 are connected by a conductor 47 to the line conductor 10. As shown, the full cycle contacts 44 and 46 are arranged to provide a direct connection between the motor 25 and the line conductor or terminal 10. In addition, reset contacts 50 are provided which may be connected by a conductor 51 to the grounded conductor or terminal 11. The reset contacts 50 are operated by a notch 52 in the code wheel 39 and close once momentarily each time that the code wheel revolves.

In operation it will be assumed that the glass on one of the fire stations FS1 through FS4 has been broken. This starts the coding mechanism CM to function and causes the code number cut on the code wheel 39 to sound four complete rounds over the fire alarm bells FB1 through FB4. Assuming now that one of the sets of contacts 14 of one of the fire stations FS1 through FS4 has been closed, box loops T1-T4 and T2-T3 are shunted so that current passes directly therethrough for energizing the series motor comprising the armature 25 and field winding 26 and causes it to start. This circuit may be traced from conductor 10 through current limiting resistor R1, contacts 14 which have been closed, normally closed contacts D1, conductor 24, armature 25, field winding 26, winding 27, conductor 28, milliammeter 29, to the grounded or neutral line conductor or terminal 11. Only a few revolutions of the series motor are required to close the full cycle contacts 44 and 46 which places the series motor in direct connection with the line conductor or terminal 10, as described above. Also, this places the terminal T6 of the fire bells FB1 through FB4 in direct communication with the line conductor or terminal 10.

As soon as the box loops T1-T4 and T2-T3 are shunted, alternating current flows through winding 33 of alarm relay C and to the half wave rectifier HWR2 and winding 32 of control relay D. On closure of reset contacts 50, the half waves of alternating current not conducted through the half wave rectifier HWR2 are effective to energize the control relay D, thereby opening main contacts D1 and closing sealing contacts D2. At the same time a holding circuit for the winding 32 is completed from the shunted box loops through the latter contacts D2 and conductor 54 to the

neutral or grounded line conductor or terminal 11. Now, so long as the fire station loops T1-T4 and T2-T3 are shunted as a result of the operation of any of the sets of contacts 14, control relay D remains energized and contacts D1 are held open. Accordingly, as soon as full cycle contacts 44 and 46 are opened as a result of the completion of the transmission of the fire alarm as described, the previously traced initial circuit for energizing the series motor is held open at contacts D1 and the motor cannot start again after the full cycle contacts 44 and 46 have again opened. Thus, it will be seen that relay D only controls the stopping of the coding mechanism after four rounds of code, but the alarm condition continues to sound, such as through alarm relay C, until the operated fire station (FS1 through FS4) has been reset to normal.

When the contacts 14 in the fire station FS1 through FS4 which have been operated are opened and the glass is replaced, the shunt between the box loops T1-T4 and T2-T3 is opened and alternating current no longer flows through the winding 32 and holding contacts D2 of the control relay D. As a result, the control relay D is de-energized and main contacts D1 are reclosed to prepare the circuit for the next operation of one of the fire stations FS1 through FS4.

As indicated hereinbefore, the present invention is directed to the provision of means for detecting and indicating the presence of a fault, such as an open circuit, grounded circuit or power failure on the system shown in the drawing. It is for this purpose that the alarm relays A, B and C are provided. The various indications that are provided on the occurrence of different types of fault will be set forth now.

If the loop circuit T1-T4 should be opened, all of the alarm relays A, B and C will be de-energized. They will then close their respective contacts A1, B1 and C1 and complete one or more signalling circuits from a separate source, such as one or more batteries to energize one or more bells, buzzers, or lamps on a suitable indicating board.

In the event that the loop circuit T2-T3 should become open, then alarm relay C will be de-energized. Alarm relays A and B will remain energized.

In the event that the fire bell circuit between the terminals T5-T6 should become open all of the alarm relays A, B and C will be de-energized.

Should there be a ground on the loop circuit T1-T4 through the fire stations FS1 through FS4, all of the alarm relays A, B, and C will drop. If the ground appears only on the loop circuit T2-T3 then only alarm relay C will drop. If the ground is on the loop circuit T5-T6 through the fire bells FB1 through FB4, only relays B and C will drop, relay A remaining energized.

If the alternating current source 12 should fail for any reason, all of the alarm relays A, B and C will drop. If the circuit through the motor having the armature 25 and field winding 26 should become open, the alarm relay B will drop. If the upper contacts D1 of the control relay D do not close, then relay C will drop.

Should rectifier HWR1 become open then all of the alarm relays A, B and C will drop. If the rectifier HWR1 becomes short circuited, relay B will drop, since it is of the low impedance type and holds on half cycles but drops on the application thereto of alternating current.

In the event that the rectifier HWR2 should become open circuited, then alarm relay C will

drop. If this rectifier should become short circuited the code mechanism CM will run continuously after a fire alarm signal has been started instead of stopping after four complete rounds of code.

In Figure 2, I have illustrated a modified embodiment of my improved system. In this embodiment, I have illustrated a single phase, self-starting synchronous motor or a shaded pole motor 25' for driving the code wheel 39 and the full-cycle contacts and rests contacts. These small synchronous or shaded pole motors are obtainable with built-in gear trains of different ratios for obtaining practically any desired speed reduction at the power output shaft. For the average installation, I have secured satisfactory performance with a 5 watt motor of this type, having an output speed of approximately 3 R. P. M. or 4 R. P. M., for driving the code wheel, etc., but it will be understood that if the requirements of different installations or different customers call for a higher or lower tempo of the coded alarm, it is a simple matter to substitute a different motor unit having the appropriate speed-reducing gear train for obtaining that higher or lower tempo of code signalling.

In this modified system of Figure 2, I have also shown a different circuit arrangement for the winding 32 of control relay D and a different control of this relay involving a different location and operation of the second half-wave rectifier HWR2. In Figure 2, this rectifier HWR2 has been taken out of conductor 34, 35 and interposed in conductor 54, and has been arranged in opposition to the first rectifier HWR1, i. e. connected to oppose the half-wave supervisory current which is transmitted through the first rectifier HWR1. Moreover, the upper end of the relay winding 32 has been connected through a conductor 34' with the fire station loop terminal T2, or upper end of alarm relay winding 33 instead of to the lower end thereof. Also, a third pair of contacts D3 is arranged to control an alarm circuit which is independently energized, similarly to the contacts A1, B1 and C1 of alarm relays A, B and C, this third pair of contacts D3 being normally open and being closed by the energization of control relay D.

The supervisory operation of the modified embodiment of Figure 2 is substantially the same as the supervisory operation of Figure 1. The fire station box loop 15, fire bells 20, fire station box, loop 16, and electric motor 25' are all continuously supervised by the half-waves of supervisory current that are transmitted through these circuits by the first half-wave rectifier HWR1. This half-wave supervisory current is not adequate to cause rotation of the synchronous or shaded pole motor 25'. However, as soon as one of the sets of contacts 14 of one of the fire stations FS1—FS4 is closed, the two half-waves or complete cycles of the alternating current are transmitted to the electric motor 25' and this motor starts operating. The operating cycle then carries on through to completion in substantially the same manner described above in connection with Figure 1.

Referring now to the different manner of controlling the control relay D embodied in Figure 2, it will be seen that normally the winding 32 is de-energized by reason of conductor 30 being open-circuited at reset contacts 50. However, in a signalling operation, consequent upon the closing of one of the sets of contacts 14 in one of the fire station boxes FS1—FS4, the operation

of the code wheel promptly closes the reset contacts 50 and thereupon the complete cycle of the alternating current is transmitted from the shunted box loops 15—16 through the relay winding 32 and reset contacts 50. The resulting energization of the relay D closes the holding contacts D2 so that the relay can be held energized by the half-wave current which the second rectifier HWR2 permits to pass over the holding circuit 54. It will be noted that the phase or polarity of the half-waves that this second rectifier HWR2 permits to pass over the holding circuit 54 is opposite to the phase or polarity of the supervisory current that the first rectifier HWR1 permits to pass over the box loops and fire bell circuit. Hence, when the contacts 14 in the fire station box FS1—FS4 are again opened, following the sounding of the four rounds of fire alarm code signalling, the stopping of the motor 25', and the opening of the reset contacts 50, the supervisory half-wave current passing through rectifier HWR1 is blocked from passing over the holding circuit 54 by the oppositely facing blocking rectifier HWR2 and hence the holding circuit is rendered non-effective to hold the relay D energized. Accordingly, this relay D is immediately de-energized and the system resumes its normal supervised condition. For example, half-wave supervisory current passing from the half-wave rectifier HWR1 over the bell circuit 21—23, would otherwise tend to flow down through motor circuit 24 and motor 25 and back up over conductor 35 to the top of relay winding 32 and thence out over holding circuit 54 for keeping this relay locked up, if it were not for the blocking action of the oppositely facing rectifier HWR2, which prevents the supervisory half-waves from rectifier HWR1 taking this path down through the motor circuit and thereby locking up the relay D. Similarly, in Figure 1, the location of the second half-wave rectifier HWR2 in conductor 35 and facing in a downward direction prevents the half-wave supervisory current from the first rectifier HWR1 passing down through the motor circuit and up over conductor 35 for locking up relay D over holding circuit 54, after the contacts 14 in the operated fire box have been restored to open position for the purpose of restoring the system to its normal supervised condition. The third pair of contacts D3 of control relay D close with the initial energization of the control relay and continue sounding an alarm as long as said relay remains energized, i. e. until the operated fire station FS1—FS4 has been reset to normal by the opening of its contacts 14 and the replacing of its glass.

The milliammeter 29 need not necessarily be connected in the circuit at the point shown in Figures 1 and 2. It can be connected in the circuit at other points where it is capable of giving a supervisory indication of the supervisory current flow. For example, it might be connected between the alarm relay A and the first half-wave rectifier HWR1, as shown in Figure 3. The synchronous or shaded pole motor 25' of Figure 2 can, of course, be employed in Figure 1 in lieu of the series motor 25, and, if desired, the embodiments of Figures 2 and 3 may have the second rectifier HWR2 located in conductor 35, as shown in Figure 1, instead of in conductor 54.

Since certain further changes can be made in the foregoing system and different embodiments of the invention can be made without departing from the spirit and scope thereof, it is intended that all matter shown in the accompanying draw-

ings and described hereinbefore shall be interpreted as illustrative and not in a limiting sense.

What is claimed as new is:

1. In a closed circuit master code fire alarm system arranged for energization from a source of alternating current one terminal of which is grounded, in combination, a first half wave rectifier connected to the ungrounded terminal of said source of alternating current, a plurality of fire bells each having a winding, a motor, circuit means connecting the aforesaid elements in series circuit relation in the order named and to said grounded terminal of said source of alternating current, a code wheel driven by said motor, a plurality of fire stations each having a pair of normally open contacts one of which is connected to said ungrounded terminal, a second half wave rectifier connected in series with said other contacts of said fire stations and to said grounded terminal of said source of alternating current; a control relay having normally closed contacts connected between the junction between said fire bell windings and said motor and the other contacts of said fire stations, and a winding connected between said second half wave rectifier and reset contacts responsive to said code wheel, signalling contacts operated by said code wheel and connected between the junction between said first half wave rectifier and said fire bell windings and said grounded terminal of said source of alternating current for energizing said windings of said fire bells, and contacts arranged to be closed on operation of said code wheel to maintain said motor energized for a complete cycle of operation of said code wheel, said first and second half wave rectifiers being connected so as to conduct the same half wave of alternating current whereby said winding of said control relay normally remains de-energized, the closure of any set of fire station contacts completing an energizing circuit through said control relay contacts to energize said motor sufficiently to drive said code wheel and energize said fire bells and to apply half waves of opposite polarity to said control relay winding to energize the same and open its contacts, thereby preventing operation of said series motor and code wheel beyond a complete cycle of operation of the latter.

2. In a closed circuit master code fire alarm system arranged for energization from a source of alternating current one terminal of which is grounded, and having an auxiliary power source, in combination, a first alarm relay having a winding connected to the ungrounded terminal of said source of alternating current, a first half wave rectifier, a plurality of fire bells each having a winding, an alternating current motor, circuit means connecting the aforesaid elements in series circuit relation in the order named and to said grounded terminal of said source of alternating current, a plurality of fire stations each having a pair of normally open contacts one of which is connected to said ungrounded terminal, a second alarm relay having a winding connected to each of the other contacts of said fire stations, a second half wave rectifier connected in series with said winding of said second alarm relay and to said grounded terminal of said source of alternating current; a control relay having normally closed contacts connected between the junction between said fire bell windings and said motor and the junction between the other contacts of said fire stations and said winding of said second alarm relay, and a relay winding connected between the other contacts of said fire stations and said grounded terminal, a code wheel driven by said series motor, contacts operated by said code wheel and connected between the junction between said first half wave rectifier and said fire bell windings and said grounded terminal of said source of alternating current for energizing said windings of said fire bells; a set of contacts normally held open by each winding of each of said alarm relays and arranged to complete an alarm circuit energized from said auxiliary power source on de-energization of any of said alarm relay windings, and contacts arranged to be closed on operation of said code wheel to maintain said series motor energized for a complete cycle of operation of said code wheel, said first and second half wave rectifiers being connected so as to conduct the same half wave of alternating current whereby said winding of said control relay normally remains de-energized, the closure of any set of fire station contacts completing an energizing circuit through

grounded terminal, a code wheel driven by said motor, contacts operated by said code wheel and connected between the junction between said first half wave rectifier and said fire bell windings and said grounded terminal of said source of alternating current for energizing said windings of said fire bells, a set of contacts normally held open by each winding of each of said alarm relays and arranged to complete an alarm circuit energized from said auxiliary power source on de-energization of any of said alarm relay windings, and contacts arranged to be closed on operation of said code wheel to maintain said motor energized for a complete cycle of operation of said code wheel, said first and second half wave rectifiers being connected so as to conduct the same half wave of alternating current whereby said winding of said control relay normally remains de-energized, the closure of any set of fire station contacts completing an energizing circuit through said control relay contacts to energize said motor sufficiently to drive said code wheel and energize said fire bells and to apply half waves of opposite polarity to said control relay winding to energize the same and open its contacts thereby preventing operation of said motor and code wheel beyond a complete cycle of operation of the latter.

3. In a closed circuit master code fire alarm system arranged for energization from a source of alternating current one terminal of which is grounded and having an auxiliary power source, in combination, a first alarm relay having a high impedance winding connected to the ungrounded terminal of said source of alternating current, a first half wave rectifier, a plurality of fire bells each having a winding, a series motor, a second alarm relay having a low impedance winding, circuit means connecting the aforesaid elements in series circuit relation in the order named and to said grounded terminal of said source of alternating current, a control relay having normally closed contacts connected between the junction between said fire bell windings and said series motor and the junction between the other contacts of said fire stations and said winding of said third alarm relay, and a relay winding connected between the other contacts of said fire stations and said grounded terminal, a code wheel driven by said series motor, contacts operated by said code wheel and connected between the junction between said first half wave rectifier and said fire bell windings and said grounded terminal of said source of alternating current; a control relay having normally closed contacts connected between the junction between said fire bell windings and said series motor and the junction between the other contacts of said fire stations and said winding of said third alarm relay, and a relay winding connected between the other contacts of said fire stations and said grounded terminal, a code wheel driven by said series motor, contacts operated by said code wheel and connected between the junction between said first half wave rectifier and said fire bell windings and said grounded terminal of said source of alternating current for energizing said windings of said fire bells; a set of contacts normally held open by each winding of each of said alarm relays and arranged to complete an alarm circuit energized from said auxiliary power source on de-energization of any of said alarm relay windings, and contacts arranged to be closed on operation of said code wheel to maintain said series motor energized for a complete cycle of operation of said code wheel, said first and second half wave rectifiers being connected so as to conduct the same half wave of alternating current whereby said winding of said control relay normally remains de-energized, the closure of any set of fire station contacts completing an energizing circuit through

said control relay contacts to energize said series motor sufficiently to drive said code wheel and energize said fire bells and to apply half waves of opposite polarity to said control relay winding to energize the same and open its contacts thereby preventing operation of said series motor and code wheel beyond a complete cycle of operation of the latter.

4. In a closed circuit master code fire alarm system arranged for energization from a source of alternating current one terminal of which is grounded and having an auxiliary power source, in combination, a first current limiting resistor connected to the ungrounded terminal of said source of alternating current, a first alarm relay having a winding, a first half wave rectifier, a second current limiting resistor, a plurality of fire bells each having a winding, an alternating current motor, circuit means connecting the aforesaid elements in series circuit relation in the order named and to said grounded terminal of said source of alternating current, a code wheel driven by said motor, reset contacts responsive to said code wheel, a plurality of fire stations each having a pair of normally open contacts one of which is connected to said first resistor, a second alarm relay having a winding connected to each of the other contacts of said fire stations, a second half wave rectifier connected in series with said winding of said second alarm relay and to said grounded terminal of said source of alternating current; a control relay having normally closed contacts connected between the junction between said fire bell windings and said motor and the junction between the other contacts of said fire stations and said winding of said third alarm relay, and a relay winding connected between said second half wave rectifier and said ungrounded terminal, a code wheel driven by said motor, contacts operated by said code wheel and connected between the junction between said first half wave rectifier and said second resistor and said grounded terminal of said source of alternating current for energizing said windings of said fire bells, a set of contacts normally held open by each winding of each of said alarm relays and arranged to complete an alarm circuit energized from said auxiliary power source on de-energization of any of said alarm relay windings, and contacts arranged to be closed on operation of said code wheel to maintain said motor energized for a complete cycle of operation of said code wheel, said first and second half wave rectifiers being connected so as to conduct the same half wave of alternating current whereby said winding of said control relay normally remains de-energized, the closure of any set of fire station contacts completing an energizing circuit through said control relay contacts to energize said motor sufficiently to drive said code wheel and energize said fire bells and to apply half waves of opposite polarity to said control relay winding to energize the same and open its contacts, thereby preventing operation of said motor and code wheel beyond a complete cycle of operation of the latter.

5. In a closed circuit master code fire alarm system arranged for energization from a source of alternating current one terminal of which is grounded and having an auxiliary power source, in combination, a first current limiting resistor connected to the ungrounded terminal of said source of alternating current, a first alarm relay having a high impedance winding, a first half wave rectifier, a second current limiting resistor, a plurality of fire bells each having a winding, an alternating current motor, a second alarm re-

lay having a low impedance winding, circuit means connecting the aforesaid elements in series circuit relation in the order named and to said grounded terminal of said source of alternating current, a plurality of fire stations each having a pair of normally open contacts one of which is connected to said first resistor, a third alarm relay having a winding connected to each of the other contacts of said fire stations, a second half wave rectifier connected in series with said winding of said third alarm relay and to said grounded terminal of said source of alternating current; a control relay having normally closed contacts connected between the junction between said fire bell windings and said motor and the junction between the other contacts of said fire stations and said winding of said third alarm relay, and a relay winding connected between said second half wave rectifier and said ungrounded terminal, a code wheel driven by said motor, contacts operated by said code wheel and connected between the junction between said first half wave rectifier and said second resistor and said grounded terminal of said source of alternating current for energizing said windings of said fire bells, a set of contacts normally held open by each winding of each of said alarm relays and arranged to complete an alarm circuit energized from said auxiliary power source on de-energization of any of said alarm relay windings, and contacts arranged to be closed on operation of said code wheel to maintain said motor energized for a complete cycle of operation of said code wheel, said first and second half wave rectifiers being connected so as to conduct the same half wave of alternating current whereby said winding of said control relay remains de-energized, the closure of any set of fire station contacts completing an energizing circuit through said control relay contacts to energize said motor sufficiently to drive said code wheel and energize said fire bells and to apply half waves of opposite polarity to said control relay winding to energize the same and open its contacts thereby preventing operation of said motor and code wheel beyond a complete cycle of operation of the latter.

6. In a closed circuit master code fire alarm system of the class described, the combination with an alternating current supply circuit, one side of which is grounded, of a plurality of fire stations, first and second conducting loops between which said fire stations are connected in parallel, one of said loops being energized from one side of said alternating current supply circuit, an alternating current motor connected to be operatively energized from said alternating current supply circuit in response to an interconnection being established between said loops through one of said fire stations, a code wheel driven by said motor, signalling contacts responsive to said code wheel, a signal circuit adapted to be energized with signalling impulses from said alternating current supply circuit through said signalling contacts, fire bells responsive to said signal circuit, a control relay for controlling the stopping of said motor after a predetermined signalling cycle, trouble relays supervising said fire station loops, signal circuit and motor, and rectifier means connected with said conducting loops, signal circuit and motor whereby one half of the alternating current wave from said supply circuit is utilized for supervision of said conducting loops, signal circuit and motor, and the full wave for signalling operation of said motor and fire bells.

7. In a system of the class described, the combination with an alternating current supply cir-

cuit, of first and second fire station loops, said first loop being connected with one side of said supply circuit, a plurality of fire stations in bridging relation between said loops, a signalling circuit connected with said first loop, fire bells interposed in series in said signalling circuit, a motor circuit connected between said signalling circuit and the other side of said supply circuit, an alternating current motor interposed in said motor circuit, a code wheel driven by said motor, signalling contacts responsive thereto for transmitting signalling impulses to said signalling circuit from said supply circuit, full cycle contacts controlling said code wheel, reset contacts responsive to said code wheel, a control relay comprising a winding and main contacts, said main contacts connecting said motor circuit with said second first station loop, and a control circuit extending from said second fire station loop through said control relay winding and said reset contacts to the other side of said supply circuit.

8. In a closed circuit, master code fire alarm system arranged for energization from an alternating current supply line, one side of which may be grounded, the combination of first and second fire station loop conductors, a plurality of fire stations connected in bridging relation between said loop conductors, a signalling circuit, signalling bells interposed in series in said signalling circuit, a control relay comprising a winding and normally closed contacts, circuit connections establishing a normally closed supervisory circuit extending from one side of said alternating current supply line through said first fire station loop conductor, signalling circuit, normally closed control relay contacts, and second fire station loop conductor in series and thence to the other side of said alternating current supply line, an alarm relay responsive to said supervisory circuit, a motor circuit connected between said supervisory circuit and the latter side of said alternating current supply line, an alternating current motor in said motor circuit, rectifier means in said system for limiting the flow of supervisory current through said supervisory circuit and through said motor circuit to half-wave current, said fire stations comprising contacts adapted upon fire station operation to establish a bridging relation between said loop conductors for transmitting full-wave alternating current to said motor, a code wheel driven by said motor, signalling contacts actuated by said code wheel connected for transmitting alternating current signal pulses over said signalling circuit to said signalling bells in a signalling operation, and cyclical control means including said control relay, winding and contacts responsive to motor operation for controlling the length of the signalling operation.

9. In a closed circuit, master code fire alarm system arranged for energization from an alternating current supply line, one side of which may be grounded, the combination of first and second fire station loop conductors, a plurality of fire stations connected in bridging relation between said loop conductors, a signalling circuit, signalling bells interposed in series in said signalling circuit, a control relay comprising a winding and normally closed contacts, circuit connections establishing a normally closed supervisory circuit extending from one side of said alternating current supply line through said first fire station loop conductor, signalling circuit, normally closed control relay contacts, and second

fire station loop conductor in series and thence to the other side of said alternating current supply line, an alarm relay responsive to said supervisory circuit, a motor circuit connected between said supervisory circuit and the latter side of said alternating current supply line, an alternating current motor in said motor circuit, a second alarm relay responsive to said motor circuit, rectifier means in said system for limiting the flow of supervisory current through said supervisory circuit and through said motor circuit to half-wave current, said fire stations comprising contacts adapted upon fire station operation to establish a bridging relation between said loop conductors for transmitting full-wave alternating current to said motor, a code wheel driven by said motor, signalling contacts actuated by said code wheel connected for transmitting alternating current signal pulses over said signalling circuit to said signalling bells in a signalling operation, a normally open relay circuit extending from said supervisory circuit through the winding of said control relay to the other side of said alternating current supply line, reset contacts responsive to said code wheel for closing said normally open relay circuit, and full cycle contacts connected between said motor circuit and said supply circuit and responsive to motor operation for controlling the length of the signalling operation.

10. In a closed circuit, master code fire alarm system arranged for energization from an alternating current supply line, one side of which may be grounded, the combination of first and second fire station loop conductors, a plurality of fire stations connected in bridging relation between said loop conductors, a signalling circuit, signalling bells interposed in series in said signalling circuit, a control relay comprising a winding and normally closed contacts, circuit connections establishing a normally closed supervisory circuit extending from one side of said alternating current supply line through said first fire station loop conductor, signalling circuit, normally closed control relay contacts, and second fire station loop conductor in series and thence to the other side of said alternating current supply line, a supervisory alarm relay interposed in said supervisory circuit between said first fire station loop conductor and said signalling circuit, a motor circuit connected to said supervisory circuit at a point between said signalling circuit and said normally closed control relay contacts and extending to the other side of said alternating current supply circuit, an alternating current motor in said motor circuit, a motor supervisory alarm relay responsive to said motor circuit, rectifier means in said supervisory circuit between said first fire station loop conductor and said signalling circuit for limiting the flow of supervisory current through said supervisory circuit and through said motor circuit to half-wave current, a supervisory alarm relay connected in said supervisory circuit between said second fire station loop conductor and the other side of said alternating current supply line, a normally open relay circuit extending from said supervisory circuit through the winding of said control relay to the other side of said alternating current supply line, said fire stations comprising contacts adapted upon fire station operation to establish a bridging relation between said loop conductors for transmitting full-wave alternating current to said motor, a code wheel driven by said motor, signalling contacts actuated by said code wheel and connected

between said signalling circuit and the other side of said alternating current supply line for transmitting full-wave alternating current signal pulses over said signalling circuit to said bells in a signalling operation, reset contacts responsive to said code wheel for closing said normally open relay circuit, and full cycle contacts responsive to operation of said motor for connecting said motor circuit directly to the first named side of said alternating current supply line.

11. In a system of the class described arranged for energization from an alternating current supply line, one side of which may be grounded, the combination of an alarm station circuit comprising parallel conductors and a plurality of alarm stations having alarm contacts therein adapted to establish a shunt connection across said parallel conductors, a bell circuit having a plurality of bells therein, a motor circuit having a motor therein, circuit connections including rectifier means for normally transmitting half-wave supervisory current from said alternating current supply through said alarm station circuit, bell circuit and motor circuit, resistor means for limiting the current flow through said circuits in the event of inadvertent grounding, means whereby the operation of one of said alarm stations transmits full-wave alternating current from said alternating current supply line to said motor, signalling contacts responsive to said motor for transmitting alternating current signalling pulses from said alternating current supply line to said bell circuit, and means for automatically controlling the duration of the signalling operation.

12. In a system of the class described arranged for energization from an alternating current supply line, the combination of an alarm station circuit comprising alarm stations having alarm contacts therein, a bell circuit having bell means therein, a motor circuit having a motor therein, circuit connections including rectifier means for normally transmitting half-wave supervisory current from said alternating current supply line through said alarm station circuit, bell circuit and motor circuit, means whereby the operation of one of said alarm stations transmits full-wave alternating current to said motor, and signalling contacts responsive to said motor for transmitting signalling pulses to said bell circuit.

13. In a system of the class described arranged for energization from an alternating current supply line, the combination of an alarm station circuit comprising alarm stations having alarm contacts therein, a bell circuit having bell means therein, a motor circuit having a motor therein, a control relay responsive to said alarm station circuit for controlling said motor, circuit connections including rectifier means for normally transmitting half-wave supervisory current from said alternating current supply line through said alarm station circuit, said bell circuit and said motor circuit, means whereby the operation of one of said alarm stations transmits full wave alternating current to said motor, signalling contacts responsive to said motor for transmitting signalling pulses to said bell circuit, a holding circuit for said control relay, and second rectifier means in said holding circuit for governing said control relay.

14. In a system of the class described arranged for energization from an alternating current supply line, the combination of an alarm station circuit comprising alarm stations having alarm contacts therein, a bell circuit having bell means

therein, a motor circuit having a motor therein, a control relay responsive to said alarm station circuit for controlling said motor, circuit connections including rectifier means for normally transmitting half-wave supervisory current from said alternating current supply line through said alarm station circuit, said bell circuit and said motor circuit, means whereby the operation of one of said alarm stations transmits full wave alternating current to said motor, signalling contacts responsive to said motor for transmitting signalling pulses to said bell circuit, and a trouble circuit including contacts responsive to said control relay for sounding a trouble alarm while said control relay remains energized.

15. In a system of the class described arranged for energization from an alternating current supply line, the combination of an alarm station circuit comprising alarm stations having alarm contacts therein, a bell circuit having bell means therein, a motor circuit having a motor therein, a control relay responsive to said alarm station circuit for controlling said motor, circuit connections including rectifier means for normally transmitting half-wave supervisory current from said alternating current supply line through said alarm station circuit, said bell circuit and said motor circuit, means whereby the operation of one of said alarm stations transmits full wave alternating current to said motor, signalling contacts responsive to said motor for transmitting signalling pulses to said bell circuit, a holding circuit for said control relay, second rectifier means in said holding circuit for governing said control relay, and a trouble circuit including contacts responsive to said control relay for sounding a trouble alarm while said control relay remains energized.

16. In a system of the class described arranged for energization from an alternating current supply line, the combination of an alarm station circuit comprising alarm stations having alarm contacts therein, a bell circuit having bell means therein, a motor circuit having a motor therein, a control relay responsive to said alarm station circuit for controlling said motor, circuit connections including rectifier means for normally transmitting half-wave supervisory current from said alternating current supply line through said alarm station circuit, said bell circuit and said motor circuit, means whereby the operation of one of said alarm stations transmits full wave alternating current to said motor, signalling contacts responsive to said motor for transmitting signalling pulses to said bell circuit, and full-cycle contacts governing said motor for producing a predetermined signalling cycle by said signalling contacts, said motor being of an alternating current type requiring both waves of the alternating current for its operation so that it does not respond to said half-wave supervisory current.

17. In a system of the class described arranged for energization from an alternating current supply line, the combination of an alarm station circuit comprising alarm stations having alarm contacts therein, a bell circuit having bell means therein, a motor circuit having a motor therein, a control relay responsive to said alarm station circuit for controlling said motor, circuit connections including rectifier means for normally transmitting half-wave supervisory current from said alternating current supply line through said alarm station circuit, said bell circuit and said motor circuit, means whereby the

17

operation of one of said alarm stations transmits full wave alternating current to said motor, and signalling contacts responsive to said motor for transmitting signalling pulses to said bell circuit, said motor being of an alternating current type requiring both alternations of the alternating current for its operation so that it does not respond to said half-wave supervisory current.

18. In a system of the class described arranged for energization from an alternating current supply line, the combination of an alarm station circuit comprising alarm stations having alarm contacts therein, an electric motor responsive to said alarm station circuit, signalling contacts responsive to said motor, a bell circuit having bell means therein responsive to said signalling contacts, means for transmitting less than the full wave of said alternating current supply line over the system and through said motor during non-signalling intervals for supervising the system, and means for transmitting

18

the full wave of said alternating current supply line to said motor during signalling intervals.

19. In a system of the class described arranged for energization from an alternating current supply line, the combination of alarm station means for initiating an alarm signal, electrically energized driving means responsive to said alarm station means, signalling means responsive to said driving means, and means utilizing a half-wave of the alternating current from said supply line for supervising said system and said electrically energized driving means.

NORMAN E. RICHMOND.
